[57] ABSTRACT

Apparatus for loading predetermined numbers of tea bags into cartons of a predetermined length comprising a rotor on which there are mounted back-to-back longitudinally extending buckets open at their opposite ends for rotation about a horizontal axis to alternately move the buckets from the upper side of the

axis to the lower side thereof, and vibrators on the rotor associated with the respective buckets operable when the buckets are moved to the lower side to effect their vibration. At one end of the rotor at the level of the bucket at the upper side there is a reciprocable transfer assembly for pushing a predetermined number of packets under light pressure into the bucket at the upper side and a conveyor including selector elements for selecting a predetermined number of packets from the supply of packets and presenting them to the transfer assembly. At the other end of the rotor at the level of the bucket at the lower side there is a support for an empty open-ended carton for supporting the carton with an open end in registration with the open end of the bucket at the lower side and a reciprocable loader assembly for discharging the inverted packets from the bucket into the carton. The loader assembly comprises a back-up member and a pusher member located at opposite ends of the bucket at the lower side of the axis, between which the packets are held, which are movable in unison to push the packets from the bucket into the carton and during such movement the pusher member is reciprocated relative to the back-up member to repeatedly squeeze the packets between the back-up member and the pusher member as the loader assembly moves the packets into the carton. Motors and limit switches provide for cyclical and sequential operation of the several components so as simultaneously to advance a selected number of packets into a bucket on the rotor at the upper side and discharge a compacted column of packets from the bucket at the lower side.

METHOD AND APPARATUS FOR LOADING TEA BAGS INTO CARTONS

BACKGROUND OF THE INVENTION

In the U.S. Pat. to Negoro, 2,826,881, there is shown a packaging machine which is designed to fill cartons with packets of powdered material and in order to condense the content of the packets so that they may be loaded into cartons of a predetermined size the packets which are filled while supported in a vertical position are turned through an angle of 90° to dispose them in a horizontal position and simultaneously vibrated to compact the content and flatten the packets. The apparatus of this invention is designed especially for inserting predetermined numbers of tea bags into cartons of predetermined length in single or double columns and to compact the tea bags by inverting them, subjecting them to vibration and to squeeze action preparatory to loading them into the carton and especially to improved apparatus for selecting predetermined numbers of packets, arranging them in single or double columns, condensing them to the predetermined dimensions of the cartons, inserting divider cards when two columns are arranged side-by-side, loading the condensed packets together with the divider cards into the cartons and supplying empty cartons for filling and discharging the filled cartons.

SUMMARY

As herein illustrated, the apparatus is designed for loading groups of predetermined numbers of envelope-like packets specifically tea bags into cartons of predetermined length and comprises a rotor rotatable about a horizontal axis, said rotor mounting a bucket for rotation about said axis from a position at the upper side of the rotor to a position at the lower side. The bucket extends longitudinally of the axis of rotation, is open at its ends and has a transverse cross-section such as to receive packets arranged on edge in a column with the packets face-to-face. A packet support is arranged at one end of the rotor at the level of the bottom of the bucket in its position above the axis and a carton support is arranged at the other end of the rotor at the level of the top of the bucket in its position below the axis. A conveyor is arranged alongside the packet support parallel to the axis of the rotor for advancing packets along the packet support toward the bucket and a conveyor is arranged at the level of the carton support transversely of the axis of rotation for advancing empty cartons onto the carton support and removing filled cartons therefrom. A transfer assembly is mounted above the packet support and comprises longitudinally spaced back-up and pusher members with the back-up member supported in the path of the advancing packets and the pusher member supported above said path. There is means for moving the pusher member downwardly into the path of the packets to confine a group of packets between the back-up member and the pusher member and means for then moving the back-up member and pusher member in unison to push the packets confined therebetween into the bucket. Selector means are mounted on the conveyor for selecting from the advancing packets a predetermined number of packets, separating them from the succeeding packets beneath the pusher member and initiating operation of the means for lowering the pusher member downwardly behind the separated packets. There is means

for rotating the rotor when the packets have been pushed into the bucket through 180° of rotation, operation of which is initiated by the movement of the transfer means to the loading position, and means for stopping the rotor at the end of 180° of rotation with the filled bucket below the axis of rotation and for simultaneously initiating operation of a vibrator mounted on the rotor for effecting vibration of the inverted bucket to promote redistribution of the content of the packets. 10 A loader assembly is provided at the lower side of the rotor for discharging the packets into the carton comprising longitudinally spaced back-up and pusher members supported at the opposite ends of the bucket at the lower side for movement parallel to the axis of the rotor with the back-up member extending through the empty carton resting on the carton support, and means operable when the bucket is moved to said position below the axis to initiate movement of the back-up member and pusher member in unison in a direction to push the packets from the bucket into the empty carton and to repeatedly reciprocate the pusher member relative to the back-up member during said movement to repeatedly squeeze the packets between them to condense the column of packets to a predetermined length no longer than that of the carton. The rotor preferably mounts two diametrically disposed buckets back-to-back so that when one bucket is at the upper side of the axis of rotation the other is at the lower side and when the bucket at the upper side is being filled with packets, packets are being discharged from the bucket at the lower side into a carton. The buckets may be designed to receive a single column of packets or may be divided longitudinally into two side-by-side compartments to receive two columns of packets and when provided with two compartments a divider is provided at the bottom of each of the buckets for receiving a divider card to maintain the column of packets separate from each other. The divider embodies several pairs of spring fingers and there is a card magazine supported at the level of the bottom of the bucket at the upper side of the rotor and a picker member supported adjacent the magazine for taking cards from the magazine and moving them into the bucket between the spring fingers. 30 40 45 50 55 The picker is connected to the transfer assembly and movable in reciprocation therewith so that as the transfer assembly is retracted to its position for receiving a predetermined number of packets the picker removes a divider card from the magazine and introduces it into the empty bucket and as the transfer means moves the packets toward the bucket the picker releases the card and is returned to its position adjacent the magazine. The conveyors, transfer assembly, loading assembly and rotor are operated cyclically and in sequence by means of suitable motors and limit switches.

The invention will now be described in greater detail with reference to the accompanying drawings wherein:

FIG. 1 is an elevation of the apparatus showing the relation of the rotor, transfer assembly, selector, carton support and loader assembly;

FIG. 2 is a similar view with the lower part of the supporting frame omitted to show the rotor in elevation with buckets above and below its axis of rotation;

FIG. 3 is an elevation, to larger scale, taken longitudinally of the rotor showing the mountings for the buckets;

FIG. 4 is a view transversely of the apparatus broken away in part to show the rotor and the vibrators for vibrating the buckets mounted thereon;

FIG. 5 is a view transversely of the rotor showing the mounting for the same;

FIG. 6 is an elevation at the lower part of the apparatus with the supporting frame omitted to show the drive for the apparatus;

FIG. 7 is a schematic for the control of the apparatus;

FIG. 8 is a plan view of the apparatus broken away in part;

FIG. 9 is an enlarged fragmentary elevation transversely of the apparatus showing a pusher member of the transfer assembly;

FIG. 10 is an elevation, partly in section, showing in detail the pusher member and back-up member of the transfer assembly;

FIG. 11 is a fragmentary enlarged elevation showing the back-up member of the transfer assembly;

FIG. 11A is a fragmentary elevation of the selector for supplying packets to the transfer assembly;

FIG. 12 is a fragmentary elevation taken transversely of FIG. 11A;

FIG. 13 is a fragmentary plan view of FIG. 11A;

FIG. 14 is a fragmentary plan view of the pusher member of the transfer assembly and valve means for initiating its operation;

FIG. 14A is a fragmentary elevation taken on the line 14A-14A of FIG. 14;

FIG. 15 is a fragmentary elevation taken on the line 15-15 of FIG. 14;

FIGS. 16 and 16A diagrammatically illustrate the safety overload clutch and drive means therefrom to the rotor shaft;

FIG. 17 is a plan view, partly in section, of the pusher member of the loader assembly taken on the line 17-17 of FIG. 6;

FIG. 18 is an enlarged fragmentary section taken on the line 18-18 of FIG. 17;

FIG. 19 is an elevation taken on the line 19-19 of FIG. 17;

FIG. 20 is an elevation, partly in section, taken on the line 20-20 of FIG. 17;

FIG. 21 is an elevation taken on the line 21-21 of FIG. 17;

FIG. 22 is an elevation of the back-up member of the loader assembly;

FIG. 23 is a plan view of FIG. 22;

FIG. 24 is an elevation taken on the line 24-24 of FIG. 23;

FIG. 25 is a fragmentary elevation of the carton conveyor;

FIG. 26 is an elevation taken on the line 26-26 of FIG. 25;

FIG. 27 is an elevation of the left-hand end of the apparatus shown in the card loading magazine;

FIG. 28 is a fragmentary plan view of one of the buckets showing the card holding fingers;

FIG. 28A is a plan view of a bucket showing additional card holding fingers;

FIGS. 29 and 30 are fragmentary sections of suction cups for taking cards from the magazine and moving them into the buckets;

FIG. 31 is a schematic of the sequence of operations; and

FIG. 32 is a schematic of the control valve.

Referring to the drawings (FIGS. 1 and 2), the apparatus comprises in general a rotor 10, a transfer assembly 12 including a selector or stacker 12a for delivering a predetermined number of packets to the rotor for inversion, a carton support 14 including means 14a for supplying cartons to the support in a position to receive the packets after inversion and a loader assembly 16 for loading the inverted packets into the carton. The aforesaid structures are assembled in operative relation on a rigid supporting frame 18 of generally rectangular structure having vertically disposed side and end supporting frame members rigidly connected by suitable cross-frame members which not only make the supporting frame rigid but provide support for the means for effecting operation of the components parts of the machine as will appear hereinafter. The rotor 10 is situated between the transfer assembly 12 and the means 14 for supplying the cartons to be filled.

The rotor 10 (FIGS. 3, 4 and 5) is mounted between transverse frame members 18a, 18b for rotation about the axis of a horizontally disposed shaft 22 (FIG. 3) supported in suitable bearings 24 and 26 (FIG. 6) mounted on the frame of the machine in the transverse frame members 18b, 18c. Rotation of the drive shaft 22 is effected by a sprocket 28 secured to one end, a drive belt 30 entrained at one end about the sprocket and about its other end about a sprocket 32, the latter being mounted on a shaft 34 journaled in suitable bearings at the base of the machine. The shaft 34 is driven, as will be described hereinafter, by a motor M.

The rotor 10 (FIGS. 3, 4 and 5) comprises spaced, substantially rectangular end frame members 36-36 which are mounted on the shaft 22 in axially spaced relation. Each end frame member 36 comprises spaced parallel bars 38-38 bolted at their opposite ends to rubber isolation mountings 40-40 which are in turn secured to mounting arms 42-42. The mounting arms 42-42 are bolted to mounting hubs 44-44, the latter being mounted on the shaft 22 and secured thereto by keys 46-46 so that the end frame members 36-36 rotate with the shaft 22. Buckets 48-48 of rectangular cross-section are mounted at their ends to the frame members 36-36 so as to be disposed longitudinally of the axis of the shaft 22 and diametrically opposite each other. Each bucket 48 comprises spaced parallel side walls 50-50, top walls 52-52 and dividers 54-54 which divide the bucket into two compartments 56-56, each of which is adapted to accommodate a column of packets with a space therebetween. The top walls 52-52 terminate short of each other so that there is a gap 58 therebetween.

Two pairs of vibrators 60-60 are mounted on supporting plates 62-62 (FIG. 3) bolted to the end frame members 36-36, each pair of vibrators being arranged to effect vibration of the two halves of the buckets 48. Air pressure is supplied to the vibrators for effecting their vibration through axially arranged passages 64-64 (FIG. 7) which extend along the shaft 22 and which are connected by a rotary valve RV at one end of the shaft to a source of air pressure by way of a bucket selector valve VL. As shown in FIG. 7, each vibrator 60 is connected by the rotary valve RV to one of the passages 64-64 and, as will appear hereinafter, only the bucket at the lower side of the axis of rotation of the shaft 22 at any time is vibrated.

According to the invention two columns of tea bags are moved by the transfer assembly 12 from right to

left, as shown in the direction of the arrow in FIG. 1, into the open right-hand end of the bucket until they fill the two compartments 56—56 from end-to-end, — the two columns being maintained separately by a divider card inserted between the dividers 54—54, as will appear hereinafter, whereupon the rotor 10 to which the buckets 48—48 are fastened is rotated through 180° thus inverting the packets and while the packets are held in the inverted position they are vibrated by actuation of the aforesaid vibrators 60—60 preparatory to being pushed from the bucket at the lower side from right to left into a carton B supported by the carton support 14.

The transfer assembly indicated generally at 12 (FIGS. 1 and 2), referred to above, is supported partly by a longitudinal extension 18c of the frame and partly by horizontally disposed, longitudinally extending, spaced parallel rods 68—68 (FIGS. 1, 2 and 8) supported at their right-hand ends in a transverse frame member 18d. The left-hand ends of the rods 68—68 are supported in the frame member 18b. The transfer assembly comprises in part a carriage 69 embodying longitudinally spaced, parallel, transversely extending bars 70—70 (FIG. 8) fastened to carriage sleeves 72—72 slidably mounted on the rods 68—68. At the right-hand end of the carriage there is mounted midway between the sleeves 72—72 on the bar 70 at that end a vertically disposed guide 74 containing a vertically disposed way 76 in which there is slidably mounted for vertical movement a support 78. Gibs 80—80 (FIG. 8) bolted to the guide 74 over the support 78 hold it in place for vertical movement. The support 78 has at its lower end a forwardly projecting block 82 to which there is bolted a downwardly extending, perpendicular pusher member 84 which is transversely flat and contains at its lower edge an upwardly extending centrally located slot 86 (FIG. 9). A rod 88 is connected at its lower end to the block 82 and at its upper end to a piston within an air cylinder 90 (packet pusher cylinder), the latter being supported by a bracket member 92 secured to the upper end of the guide 74.

The carriage 69 is movable longitudinally on the rods 68—68 by means of an air cylinder 94 (pusher carriage cylinder), FIGS. 1 and 8, supported above and parallel to the rods 68—68 by the frame member 18b. The air cylinder 94 is provided with a rod 96 which extends from its right-hand end and is connected at its distal end by a clevis 98 (FIG. 10) to the upper end of a post 100, the lower end of which is fixed to the carriage bar 70 at the right-hand end. By supplying air pressure to the cylinder 94 at appropriate time the carriage may be reciprocated longitudinally relative to the rotor. The transfer assembly is situated above a horizontal tabe 104 supported by the frame member 18c to which columns of packets are delivered by the selector or stacker 12a, as will appear hereinafter.

With the carriage 69 in its extreme right-hand position (FIG. 1), the elevated pusher member 84 is lowered by supplying air to the cylinder 90 to a position behind the columns of packets resting on the horizontal support 104 whereupon air pressure is supplied to the cylinder 94 to advance the carriage from right to left to cause the pusher member 84 to push the columns of packets along the support 104 into the open end of the bucket 48 at the upper side of the rotor.

It is desirable to support the leading packets upright and to apply an initial light compaction to the columns

of packets as they are moved into the bucket. Accordingly, there is mounted on the carriage bar 70 at the left-hand end (FIGS. 1, 2 and 10) a packet support member 105 supported in a vertical position parallel to the pusher member 84. The support member 105 is transversely flat and has at its lower edge an upwardly extending slot 106 (FIG. 11). The support member is fastened to a bracket plate 108 (FIGS. 8 and 10) slidably mounted on a pair of vertically spaced, parallel, longitudinally extending rods 110 and 112 secured at their right-hand ends to the carriage bar 70. A stop collar 114 (FIG. 8) is fastened to the rod 110 a predetermined distance from the carriage bar 70 and a coiled spring 116 is mounted about the rod 110 between a spring guide 118 encircling the rod 110 and the bracket plate 108 which yieldably urges the support member 105 toward the left. This allows the carriage to move the support member up to the stop collar 114 to compress the columns of packets.

The frame members 18a, 18b contain openings for receiving, respectively, the support member 105 and the pusher member 84 so as to be substantially flush with the ends of the rotor and thus to hold the packets in the buckets under light compression in the buckets until they are rotated.

The packets are supplied to the transfer assembly 12 in double columns by the selector or stacker 12a (FIGS. 11A, 12 and 13) which advance the packets in two columns with the packets face-to-face and comprises conveyors arranged along the opposite sides of the support 104, — these conveyors being shown as endless chains 122—122 mounted on sprockets 124—124 so that portions of the chains between sprockets move along the opposite sides of the support 104. Selector fingers 126—126 are mounted on the chains at intervals such as to intercept predetermined numbers of packets and advance them in columns to the transfer assembly. The selector fingers 126—126 are pivotally mounted on blocks 128—128 for tilting movement about horizontal shafts 130—130 and the blocks 128—128 in turn are pivotally mounted for rotation about vertical shafts 132—132 on the conveyors.

The selector fingers 126—126 have upwardly projecting trips 134—134 arranged to pass beneath leaf spring cam members 136—136 and to be tilted thereby to push the selected groups of packets ahead of them forwardly approximately three-fourth of an inch so that there will be gaps between the trailing packets of the selected groups and the leading packets of the succeeding packets. As the selector fingers 126—126 are tilted the left-hand mounting block 128 looking in the direction of travel presses a valve BVo (FIGS. 14 and 15) which causes the cylinder 90 to move the pusher member 84 down into the gaps. When the pusher member completes its descent a cam 138, then by engagement with a button 140, bleeds the valve BVo which supplies air to the pusher carriage cylinder 94 to cause the carriage to transfer the groups of packets ahead of the pusher member 84 into the bucket at the upper side of the rotor. The valve BVo is mounted on a horizontal bracket plate 142 which in turn is mounted to the frame on supports 143—143 (FIG. 15). Actuation of the valve BVo is effected by means of a follower 144 which is engaged by the block 128, the follower being mounted at one end of an arm 146 fixed to a shaft 148. An arm 150 fixed to the shaft 148 is arranged with an

end opposite the valve BV_0 and is provided with an adjustable actuator 152 for engagement with the valve. The bracket also supports the button 140, the leaf spring members 136-136 and a buffer stop 154.

The carriage has mounted on the bar 70 at its left end an actuator 155 (FIGS. 1, 2 and 11) which is operable when the carriage reaches the end of its movement to press a microswitch MS^1 . The microswitch MS^1 is in series with a second switch MS^2 , that is, held closed by the carton loader pusher member to be described hereinafter when it is retracted, that is, in its position at the right-hand end of the bucket at the lower side of the rotor. The combined signals from these two switches MS^1 , MS^2 (FIG. 17) passes through an electrical relay R and momentarily energizes a solenoid S which operates a single revolution clutch 156 (FIG. 6) which, as will be described in greater detail hereinafter, drives the sprockets 32 and 38 about which the belt 30 is entrained to rotate the inverter through 180° thus to bring the packets in the top bucket to the bottom and thus invert them.

As the rotor completes its 180° rotation a cam 160 (FIG. 16) on the output flange 162 of an overload clutch 164 to which the pulley 32 is attached operates through a pivoted bell crank lever 166 to depress a valve VP which supplies pressure to the carton loader assembly, to be described hereinafter, to cause it to discharge the packets from the bucket 48 at the lower side of the rotor and simultaneously to start the vibrators on the bucket at the lower side of the rotor.

The loader assembly comprises a pusher member 167 (FIGS. 2, 6 and 17) which moves through the bucket and pushes the packets from the bucket and a back-up member 168 (FIGS. 22 and 23) which in cooperation with the loader member applies light pressure to the packets as they are moved from the bucket into the open end of the carton. The pusher member 167 is connected to the forward end of a piston rod 172 (FIG. 18) mounted in a cylinder 174. The cylinder 174 is mounted in a tube 176. One end of the tube 176 is fastened to a bracket plate 178 (FIG. 19) by means of which it is bolted to the frame member 18a of the machine. The other end extends through a sleeve bearing 180 in the tube 176 and is fixed in a clamp plate 186 (FIGS. 17 and 20) supported on trunnions 185-185 mounted in blocks 188-188 bolted to a plate 184 which in turn is bolted to a frame member 18f of the machine.

The pusher member 167 (FIG. 19) is transversely flat and has in its upper edge a slot 190. The pusher member 167 is bolted to a bracket plate 192 fastened to the arm of a bracket 196. The bracket 196 is mounted on a block 198 on which is mounted a bearing 200 slideable on one of the two guide rods 202-202 (FIG. 6), the latter being fixed at one end in a hanger 204 and at their other ends in a post 206 supported on the frame by a cross-plate 207.

The connection between the pusher member 167 and the rod 172 (FIG. 18) is provided for by a circular opening in the bracket plate 192 peripherally of which there is a re-entrant annular groove 208 and a flanged coupling element 210 threaded on the rod with the flange engaged within the annular groove 208. Movement of the pusher member 167 from right to left through the bucket at the lower side of the rotor will push the packets from the bucket into a carton B sup-

ported on the carton support 14 at the left-hand end of the rotor 10.

To apply pressure to the packets during such discharge movement there is provided, as previously mentioned, a back-up-member 168 which is supported in alignment with the open end of the bucket at the lower side of the rotor on a piston rod 212 extending from a cylinder 214 (FIGS. 22, 23 and 24). The cylinder 214 is supported at one end by a clamp bracket 216 bolted to a slide plate 218 mounted in a way 220 formed in a support 222 and retained therein by gibs 224-224. The support 222 is provided with a mounting bracket 226 by means of which it is bolted to the frame of the machine. A bearing block 228 mounted at the upper end of a bracket 230 provides support for a bearing 232 through which the rod 212 passes. The bracket 230 is mounted on a guide rod 231 which is supported at its ends by a bracket 233. The bearing block 228 has laterally extending arms 234-234 through which extend guide rods 236-236. The left ends of the guide rods 236-236 are connected by a yoke 238 (FIG. 24) and the right ends are fixed to the back-up member 168. By supplying pressure to the cylinder 214 the piston rod 212 may be moved horizontally across the carton support 14 through a carton resting thereon to position the back-up member 168 adjacent the open end of the bucket on the rotor.

With the back-up member 168 extended through the carton adjacent the open end of the bucket the pusher member 167 is moved into engagement with the packets in the bucket at the opposite end whereupon both members are moved from right to left to transfer the packets to the carton, the movement being such that the back-up member is withdrawn at a slower rate than the pusher member is advanced to apply squeezing action to the packets. At the end of the discharge the two members are flush with the ends of the carton.

It is desirable to compress the packets as they are discharged into the carton and this is accomplished by a light squeezing action between the back-up member 168 and the pusher member 167 while all the time vibrating the lower bucket. The pressure is applied by moving the pusher member forwardly, then retracting it about an inch and then immediately extending it again and repeating this action two or more times at predetermined intervals during the initial part of the discharge cycle. The alternate squeezing relaxing action on the packets together with the vibration aids redistribution of the carton of the packets and enables the groups of packets to be reduced to a minimum possible length, that is, so as to fit within the carton length provided for holding the packets.

As previously related when the rotor 10 rotates the bucket at the top side to the lower side a cam 160 (FIG. 16) actuates a valve VP to supply pressure to the cylinder 174 to move the pusher member 167. Simultaneously a programmer P (FIG. 7) so labeled is started and causes the pusher member 167 to be retracted about an inch and then immediately extended again to produce the squeezing and relaxing action referred to. During the initial part of the cycle of operation of the discharge assembly the back-up member 168 remains extended through the carton and acts as a support for the packets while they are being compressed. When the group of packets reaches its minimum length a cam 240 which is moved along with the pusher member presses a valve BV^3 which turns off the vibrators and supplies

pressure to the back-up cylinder 214 to retract the back-up member 168. The valve BV³ is mounted on a bracket 242 (FIG. 6) bolted to the frame and is actuated by an actuating member 244 supported in the path of movement of the cam 240 on a guide rod 246 parallel to the direction of movement of the cam 240. The guide rod 246 provides for adjustment of the valve actuator longitudinally with reference to the path of movement of the cam 240. The speed of the back-up member 168 is adjusted so that it travels slower than the pusher member 167 and thus the pusher member 167 applies pressure to the packets as the two members travelling in unison discharge the packets into the carton. When the groups of packets are completely within the carton the pusher member which is fully extended comes to a stop and remains flush with the open end of the carton. The back-up member is completely retracted and remains flush with the opposite end of the carton. In this way the packets are held within the carton until the carton is moved on for folding and glueing of the end closure members. Suitable guides are provided along the path of movement of the carton as it is moved onto the folding and glueing means to continue to hold the packets within the carton.

The cartons are delivered to the carton support 14 by conveyor chains 250-250 (FIGS. 25 and 26) mounted on sprockets 252-252 transversely of the axis of the rotor with a horizontal run at the level of the bucket at the lower side of the rotor. The conveyor chains 250-250 carry spaced parallel upstanding fingers 254-254 between which the cartons are disposed and advanced along the support 14 to the position of loading. Two microswitches MS⁴, MS⁵ wired in series are contacted, the switch MS⁴ by the back-up member when it is fully retracted and the switch MS⁵ by the pusher member when fully extended produce a signal which indexes the conveyor to move the loaded carton from the support 14 from between the pusher member and back-up member forwardly between guide rails which hold the packets within the carton, as previously related. At the same time an empty carton is moved onto the support between the back-up member and pusher member. A cam CO (FIG. 25) on the conveyor then presses a valve BV⁶ which causes the pusher member cylinder to retract and the back-up member cylinder to extend the back-up member through the empty carton. The two members then remain in this position awaiting rotation of the rotor.

At the completion of 180° of bucket rotation a cam BC on the shaft actuates a bucket valve VL to start the carton loading cycle over by causing the cylinder 90 to raise the pusher member 84. Elevation of the pusher member 84 contacts a bleeder valve BV¹ (FIG. 7) on the frame which causes the carriage cylinder 94 to return to its initial position. The pusher carriage remains in this position until the selector member again actuates the valve BV¹ to start the carriage forwardly.

In order to maintain the two columns of packets in the carton separate from each other divider cards DC are inserted between the two columns prior to insertion. The cards are stacked in a magazine 260 (FIG. 27) supported in an inclined position by means of brackets 262-262 mounted on a pair of horizontally extending rods 264-264 fixed to the frame above the carton conveyor, with its lower end adjacent the upper bucket on the rotor. The magazine has at its upper end a support 266 and at its lower end supports 268 which

support the cards in a stack 270 vertically. In order to hold the upper ends of the cards at the lower end of the stack upright there are provided hook fingers 272-272 having portions 274-274 parallel to the bottom of the magazine which engage the upper edges of the cards and hooks 276-276 which engage the forward side of the endmost card at the lower end. The endmost card is supported by the magazine on the center line of the bucket shaft and before the groups of packets are pushed into the upper bucket the endmost card is removed from the magazine and inserted between the dividers 54-54 at the bottom of the bucket and to make sure that it stays in place and does not fall out when the bucket is inverted three pairs of spring fingers 278-278 (FIG. 28) are mounted between the dividers 54-54 in the space between them. The fingers 278-278 are spaced at their entrance and converge from right to left, so that as a card is drawn through the space between the dividers it will be securely gripped and held in a vertical position by the spring fingers.

The divider cards are then removed from the magazine and introduced into the divider at the bottom of the bucket by a card feeding device which comprises a card support 280 which has a longitudinally disposed flat lower end 282 on which there are mounted two suction cups 284-284 (FIGS. 27, 29 and 30) arranged in confronting relation to the lowermost card in the magazine. A cylinder 286 is mounted on the lower end 282 of the support 280 which contains two pistons 287-287 to which the suction cups are connected. The support 280 is suspended at its upper end on the forward ends of the rods 110 and 112 (FIG. 27), the latter, as previously described, being connected to the forward bar 70 of the pusher carriage. The support 280 is accordingly reciprocably movable with the pusher carriage and is moved thereby during retraction from a position confronting the card magazine through the upper bucket to draw a card from the magazine through the bucket into the gap between the dividers 40 in the bucket. When the pusher carriage is extended to a position over the bucket the suction cups 284-284 confront the lowermost card in the magazine and in this position a cam 288 on the support 280 presses a bleeder valve BV¹⁰ bolted to the carriage cylinder 94. This causes a vacuum to be applied to the card feed cylinder 286 which moves the pistons forwardly, bringing the suction cups into contact with the lowermost card in the magazine. At this point the vacuum causes the suction cups to firmly grip the card. When the pusher carriage receives its signal to return, the cylinder 286 which moves with the carriage slides a card from the magazine into the bucket between the dividers. At a predetermined position a second bleeder valve BV¹¹ is depressed by the cam 288 on the support 280 which causes the suction cups to release the card and retract from its opposite sides, leaving the card gripped in the spring fingers in the bucket. When the pusher carriage returns from right to left bringing two groups of packets into the bucket the suction vacuum cups which are in their retracted positions are withdrawn from the bucket leaving the card in the bucket between the packets newly introduced.

During the carton loading operation the divider card is pushed from the center dividers by the pusher member 167 and transferred with the packets into the carton. Just prior to the discharge of the packets the pusher member 167 may compress the groups of pack-

ets to a distance that is less than the carton length and thus the distance between the pusher member 167 and the back-up member would be less than the length of the card. To prevent damage to the card it is allowed to enter a slot 213 (FIG. 23) in the back-up member 168 and when the discharge is completed stripper fingers 294-294 (FIG. 22) mounted on the back-up cylinder stop insure that the card is held correctly positioned in the carton. During the discharge of the packets from the bucket the vibration and jerking action of the pusher member may cause the divider card to fall out of the bucket in spite of the gripping fingers 278 which are designed to hold it in place. To overcome this two nylon retainer fingers 296-296 (FIG. 28A) are mounted on the bucket so as to extend across the open top on pivots 300-300 and spring loaded by means of a spring 302 so that they will pivot away to allow the pusher members to pass freely through the bucket.

The buckets have been described as being divided into two chambers so as to receive two columns of packets; however, it is within the scope of the invention to employ buckets with a single chamber for receiving a single column of packets. When employing buckets with a single chamber the card magazine and feed means for the cards are dispensed with. It is also within the scope of the invention to provide for substituting rotors with buckets of different length to enable loading cartons of different length with packets. Accordingly, the machine is provided with adjustments to enable substituting rotors of one size for another and to enable adjusting the positions of the limit switches which control the sequence of operation for the bucket length employed.

The drive which was briefly referred to heretofore comprises (FIG. 6) a gear reducer R driven by a motor M, a single revolution clutch 156 and an overload clutch 164. The output shaft 301 of the gear reducer is connected by an adapter 303 to the input hub 305 of the single revolution clutch 156. The output hub 158 of the single revolution clutch is keyed to the shaft 34 which runs in ball bearings and the overload clutch 164 is carried on this shaft with its input hub 307 clamped to it. The sprocket 32 is 12-toothed and is clamped to the output flange 162 of the overload clutch and the drive is transferred by this sprocket to the sprocket 28 on the bucket shaft which has 24 teeth by way of the belt 30.

The single revolution clutch 156 has an outer collar 309 with a step cut in it and engaged within this step is a spring loaded pawl pivoted to the clutch mounting plate 315. When the apparatus is in use the input hub 305 turns continuously while the collar is held stationary by the pawl and when the signal is given for the buckets to rotate the pawl is lifted by a solenoid and instantly released again. This momentarily releases the collar which in turn releases the clutch brake and connects the input hub 305 to the output hub 158. The collar then begins to rotate together with the input and output sections of the clutch. During this time the pawl rides on the cam-shaped surface of the collar. When one revolution of the output hub 158 has been made the pawl engages the step in the collar which disconnects the input and energizes the brake. The output of the clutch then becomes locked and cannot be rotated in either direction while the input hub continues to rotate freely.

The overload clutch drives the output flange 162 through a spring-loaded pawl 311 (FIGS. 16 and 16A) which engages a V-shaped groove 313 on the input hub 162. If for any reason the bucket starts to rotate and then becomes jammed the input hub 162 which is driven by the single revolution clutch will continue to turn and lift the pawl 311 out of the V-shaped groove 313. The input hub 162 is then free to complete the remainder of its one-revolution after which it comes to rest. At this point the overload pawl 311 will remain disengaged and the operator must free the jaw and turn the buckets back to re-engage the pawl.

The air circuit is designed so that all functions on the loader are sequential, that is, the completion of any one function initiates the next. If a complete cycle is considered as beginning when the loader is in the position shown in the loader schematic then a summary of the functions in each cycle is given in the accompanying chart (FIG. 31). When reading this chart start at sequence 1 and follow the solid lines from their source to the arrow heads and read from left to right. The plus signs indicate the extend stroke of the piston rods in the cylinders and the minus signs indicate the retract strokes. The output of sequences 3 and 14 are required to start the bucket rotation sequence 4. The machine shut-down pressure switch will operate when the output from sequence 1 is present and the output from sequence 6 is not present. The machine shut down pressure switch will operate when the output A from sequence 1 is present and the output B from sequence 6 is not present. When output A and output B are present A + B will start the loader.

During its normal operation the loader must cycle rapidly enough to allow the pusher carriage to return in sufficient time to receive the packets as they are delivered by the stacker. If a delay in the loader cycle causes the pusher carriage to return late, valve VN in the loader schematic (FIG. 7) will cause the machine to shut down in the following manner:

When the pusher carriage is in the correct position the plunger of valve VN is depressed and the "out" port is connected to the "in" port. In this position a signal from the stacker will cause air to be bled from line L⁷ through the bleed valve on the stacker trigger assembly.

If the pusher carriage is not forward the plunger of valve VN will not be depressed and the "in" port will be connected to the "out" port. In this situation a stacker signal will bleed line L¹⁷ instead of line L⁷.

In the control box schematic (FIG. 32) line L⁷ is shown as being connected to the right-hand side of valve VC (via the "out" port of valve VD). When line L⁷ is bled, the spool of valve VC will shift to the right causing the pusher member to descend which will start the loader on its normal cycle.

Line L¹⁷ of FIG. 32 is connected to the right-hand side of valve VH and when line L¹⁷ is bled, the spool of valve VH will shift to the right which will shut off the air supply to pressure switch line L¹⁸ at the same time opening line L¹⁸ to the atmosphere. Loss of air pressure to the switch VH will cause the machine to shut down. A three-way "retained toggle" miniature valve VU (FIG. 7) is mounted on the trigger bleeder valve BV₀. When the toggle is moved to the "closed" position the valve prevents both line L⁷ and line L¹⁷ from being bled, thus stopping the inverter loader and in turn the cartoner but keeping the rest of the machinery in oper-

ation. The toggle in the "open" position allows inverter loader to function normally.

On bleed type valves air is fed to each end of the spool, through internal passages in the valve to each end of the spool. In this manner the spool normally remains in equilibrium and shifts only when one of the valve pilot lines is opened to atmosphere. However, when one of the pilot lines on the valve is greatly longer than the other and air is suddenly applied to the "in" port, pressure will build up on the side of the valve connected to the shorter line and may cause to spool to shift to the side connected to the longer line.

This condition exists on valve VC (FIG. 32) where pilot line L⁷ on the righthand side of the valve is greatly longer than the pilot line connection at the left.

Air is supplied to the reservoir through valve VM and may be turned on and off rapidly during the normal loader cycle. For this reason valve VD is incorporated into the circuit to balance valve VC in the following manner:

When the air supply to the reservoir is off, valve VD shuts off pilot line L⁷ at a short distance from the right-hand side of valve VC. This in effect makes the right-hand pilot line of valve VC the same length as the left.

This situation remains when air is initially applied to the reservoir, allowing pressure to build up equally on both sides of valve VC. However, when the pressure in the bleed system reaches approximately 20 psi the pilot valve VD which is connected to the bleed system manifold causes valve VD to reconnect the longer pilot line L⁷ to the right-hand side of valve VC.

During the time that it is shut off line L⁷ must be maintained at system pressure by an alternate means since it cannot receive air from valve VC as it would otherwise cause the spool of valve VC to shift when it is reconnected. For this reason a continuous air supply is applied to the "out" port of valve VD and therefore when pilot pressure to the pilot of valve VD is below 20 psi the "in" port is shut off and the "out" port (continuous air supply) is connected to line L⁷.

When the pilot pressure to valve VD is above 20 psi the "out" port (continuous air supply) is shut off and the right-hand side of valve VC is connected to line L⁷.

The check valve VR is inserted into the short pilot line between valve VD and VC to prevent feed back of the continuous air supply to valve VC when the valve VD switches.

The control box schematic (FIG. 32) shows a three-way pilot valve VA inserted between the pilot lines of pusher carriage cylinder directional control valve VB. The purpose of this valve is to insure that the pusher carriage cylinder cannot extend without a prior signal being given to retract the pusher member. Conversely, it insures that the pusher carriage cylinder cannot retract without the pusher member being extended. These situations would otherwise occur if an operator accidentally pressed either bleed valve BV¹ or BV².

The right-hand pilot line of valve VB is connected to the "in" port of valve VA. The left-hand pilot of valve VB is connected to the "in" port of valve VA. Bleed valves BV¹ and BV² are joined together on the "out" port of valve VA. With the pusher member retracted, pressure is applied to the pilot port of valve VA connecting the right-hand pilot of valve VB to bleed lines L¹ and L². In this manner the spool on valve VB can

only shift to the right after which lines L¹ and L² will have no further effect.

When the pusher member extends, pilot pressure on valve VA is removed (since line L⁵ is exhausted to atmosphere) and the left-hand pilot line of valve VC is connected to lines L¹ and L². The spool in valve VC can then only shift to the left after which lines L¹ and L² will again have no further effect.

Air is supplied to the vibrators by a rotary valve RV 10 which transmits the air to two axial holes 64—64 in the bucket shaft 22. The valve RV which is located at the end of the bucket shaft is secured to the loader frame to prevent it from turning. Referring to the loader schematic (FIG. 7) the rotary valve RV has two adjacent air 15 supply ports, one of which is always in line with a radial hole drilled in the bucket shaft, as shown at the left of the valve. A central O ring seal prevents leakage between the adjacent air supply ports. Air is supplied from valve VE in the control box to line L⁸ connection 20 on three-way cam operated bucket selector valve VL. FIG. 7 shows the spool in the valve VL shifted to the right and air is crossing from line L⁸ to the left-hand port of VL which is in turn connected to the left-hand port of the rotary valve RV. The air is then admitted to 25 the lower axial hole in the bucket shaft through the adjacent radial connection hole and thus starts the vibrators on the lower bucket. At the completion of the next loader cycle the bucket shaft will have rotated 180° and the spool on valve VL will have shifted to the left. Air then crosses from line L⁸ to the right-hand port of valve VL which is connected to the right-hand port of the rotary valve RV. In this way air is admitted to the second axial hole which is now the lower one and again supplies only the vibrators on the lower bucket.

35 When the carton loader cylinder is on its extend stroke the cam 240 on the carton loader packet pusher passes over the bleed valve BV³ which turns the vibrators off and causes the back-up cylinder to retract. Referring to FIG. 7 the bleed valve BV³ is shown as being 40 attached directly to the center port of valve VK. The purpose of valve VK is to isolate the bleed valve BV³ from the circuit while the carton loader cylinder is on its retract stroke. This is to prevent the bleed valve from signalling the back-up cylinder to retract a second time when the cam 240 on the carton loader cylinder passes over it again on its retract stroke.

45 Valve VK is shown with pilot pressure line 11A holding the spool to the left. The control box schematic (FIG. 32) shows that pilot line 11A is connected to the carton loader cylinder retract power line L¹¹. This means that line L¹¹ is pressurized when the carton loader cylinder is retracted and is unpressurized when the cylinder is extended.

50 Pilot bleed line L⁹ is shown in FIG. 7 as connected to the left-hand port of valve VK, the port being shut off since line 11A is pressurized. The bleed valve BV³ is therefore isolated from line L⁹ and the rest of the circuit.

55 When the carton loader cylinder extends line 11A is unpressurized and the spool in valve VK shifts to the right thus connecting the bleed valve BV³ to the left-hand port and line L⁹.

60 Most of the control valve switching is carried out by two types of pilot bleed valves on the loader. The first type consists of a plunger with an O-ring seal at the end, mounted in the valve body. The valve body is screwed into a mounting to which the bleed lines is attached and

when the plunger is depressed air escapes from the bleed line until the plunger is released.

All bleed type control valves require that the pilot signal be applied only for the time it takes the valve to switch and then the signal must be removed. Pilot bleed valves of the first type are therefore used only when the cam operating them moves away immediately after doing so.

In certain cases when a pilot bleed valve is not released during a cycle, or there is a possibility that this may occur, a second type known as a "recycling bleed valve" is used. This type of valve momentarily bleeds the line when the button is depressed then reseals. The button must then be released before the valve will operate again.

Under normal operating conditions the air supply may be shut off during the loader cycle. This can occur at the instant the buckets are signaled to rotate upon which the loader clutch shaft will rotate one revolution and signal the carton loader extend and vibrators VB to bleed line L¹³. But since the loader air supply has been shut off the loader cannot complete its cycle and may be required to remain at rest for an indefinite period of time. When the air supply is restored, the loader must carry on to complete its cycle and in order to do so, line L¹³ must momentarily bleed to atmosphere then reseal. For this reason a normal bleed valve is substituted by a cam operated pilot return three-way valve VP as shown in FIG. 7. With the spool on valve VP shifted to the right line L¹³ is shut off. When the clutch shaft rotates a cam 160 on the clutch shaft shifts the spool to the left which opens line L¹³ to atmosphere. This causes line L¹⁰ to pressurize and extend the carton loader cylinder. Line 10B which is connected to line L¹⁰ also pressurizes and shifts the spool in valve VP back to the right which shuts off line L¹³.

When the carton loader cylinder is retracting, exhaust air would normally flow along line L¹⁰ and through valve VP but cannot do so because of the presence of the pressure regulator on line L¹⁰. A quick exhaust valve VT is therefore inserted into line L¹⁰ to allow exhaust air to escape to atmosphere prior to entering the pressure regulator.

Quick exhaust valve VS is inserted into line L^{11B} to allow rapid recovery of the carton loader cylinder extend stroke during the programmed portion of its cycle.

As previously mentioned the carton loader cylinder is given a jerk motion to alternately squeeze and release the pressure on the packets during the compression part of its cycle. To achieve this motion a three-way valve VQ (mounted in the programmer, FIG. 21) is introduced into the carton loader cylinder retract line L¹¹.

Referring to FIG. 7, valve VQ is shown in its de-energized position with line L¹¹ connected to the left-hand port. Line L²² which is continuously pressurized is shown connected to the right-hand port and the valve "out" port is connected through the programmer manifold to the carton loader cylinder retract side. In this position air is being supplied to line L¹¹ and is passing through valve VQ to the "out" port and retracting the carton loader cylinder. Line L²² in the meantime is shut off by valve VQ. During the normal carton loader cylinder extend stroke line L¹¹ is open to atmosphere, thus allowing exhaust air to escape through the quick exhaust valve VS. At a predetermined time after the car-

ton loader cylinder begins its extend stroke, the solenoid SQ of valve VQ is energized by the programmer. This causes the spool to shift to the left and connect pressurized line L²² to the "out" port and therefore the retract side of the cylinder. At this moment pressure regulated air at approximately 30 psi is being supplied by line L¹⁰ to the extend side of the cylinder and air at 60 psi is being supplied to the retract side.

The higher pressure air causes the cylinder to begin 10 retracting, at which point the programmer de-energizes the solenoid SQ of valve VQ causing line L²² to be shut off and line L¹¹ to be again open to atmosphere. The cylinder then rapidly extends again until resisted by the pressure of the bags.

15 The programmer is set to energize the solenoid of valve SQ three times in the following pattern:

Carton loader cylinder starts extend stroke — (time delay) — solenoid energized — (time delay) — solenoid de-energized — (time delay) — solenoid energized — (time delay) — solenoid de-energized — (time delay) — solenoid energized — (time delay) — solenoid de-energized.

20 Each of the above time delay sequences is controlled by an electrical relay which is set when the programmer is assembled and once the programmer is started, each relay will automatically operate in sequence until the program is complete.

25 The programmer is started by a pressure switch on line L^{10a} which is connected to the carton loader cylinder extend line L¹⁰.

If the program cycle is not complete by the time the back-up cylinder is given its signal to retract the program is cancelled by a pressure switch on line L^{15a} which is connected to the back-up cylinder retract line 35 L¹⁵.

For each count the length of each time delay sequence is different and therefore the program is set according to the count required. Several programs may be catered for by means of variable potentiometers.

40 As an aid to supporting the pockets upright as they are moved along the support 104 toward the back-up member 105, nozzles N-N may be mounted on the back-up member so as to project jets of air toward the leading ones of the pockets. These nozzles are illustrated as set into openings in the back-up member, are movable with the back-up member and are supplied with air under pressure from a suitable source.

45 It should be understood that the present disclosure is for the purpose of illustration only and that this invention includes all modifications and equivalents falling within the scope of the appended claims.

I claim:

50 1. Apparatus for loading tea bags into cartons comprising a rotor supported for rotation about a horizontal axis for receiving in one position parallel to its axis of rotation a column of tea bags arranged on one edge face-to-face and in another position to support the bags inverted, means for effecting rotation of the rotor from the one position to the other to successively receive columns of packets and invert them, means for supporting an open-ended carton at said position of inversion of the packets, and means for pushing the packets from the rotor into a carton resting on said support.

55 2. Apparatus according to claim 1, comprising means for moving a column of bags onto the rotor and simultaneously applying compacting pressure to the ends of the column as it is moved onto the rotor.

3. Apparatus according to claim 1, comprising means for vibrating the bags while supported in their inverted position.

4. Apparatus according to claim 1, wherein the means for discharging the bags from the rotor into the carton operates to apply compressive pressure to the ends of the column as it is moved from the rotor into the carton.

5. Apparatus according to claim 1, wherein said means for discharging the bags from the rotor into the carton operate to apply repeated squeezing and releasing pressure to the bags in the column as the column is advanced along the rotor toward the carton.

6. Apparatus for loading groups of a predetermined number of envelope-like packets into a carton comprising a rotor rotatable about a horizontal axis, a bucket mounted on the rotor for rotation from a predetermined position above said axis to a predetermined position below said axis, said bucket having open ends for receiving packets supported on edge face-to-face, a packet support at one end of the rotor in alignment with the position of the bucket when the bucket is above said axis, a transfer assembly movable along the packet support parallel to the axis of the rotor for moving a predetermined number of packets along the support into the bucket above said axis, a carton support at the other end of the rotor for registration with the bucket when below said axis such that the open end of the carton on the carton support will be in registration with said other end of the bucket, a loader assembly supported in alignment with the carton support for movement parallel to the axis of rotation of the rotor operable to push the packets from the bucket below the axis into the carton, and driving means for effecting operation of the transfer assembly, the rotor and the loader assembly to cause a selected number of packets to be moved into the bucket above said axis, rotate the bucket to invert the packets and discharge the packets from the inverted bucket into the carton.

7. Apparatus for loading groups of a predetermined number of envelope-like packets into a carton comprising a rotor rotatable about a horizontal axis, a bucket mounted on the rotor for rotation from a predetermined position above said axis to a predetermined position below said axis, said bucket having open ends for receiving packets supported on edge face-to-face, a packet support at one end of the rotor in alignment with the position of the bucket when the bucket is above said axis, means for advancing packets along said packet support toward said rotor, a transfer assembly movable along the packet support parallel to the axis of the rotor for removing a predetermined number of packets from the advancing packets and pushing them into the bucket above said axis, a carton support at the other end of the rotor for registration with the bucket when below said axis such that the open end of the carton on the carton support will be in registration with said other end of the bucket, a loader assembly supported in alignment with the carton support for movement parallel to the axis of rotation of the rotor operable to push the packets from the bucket below the axis into the carton and driving means for effecting operation of the means for advancing the packets, the transfer assembly, the rotor and the loader assembly to cause a selected number of packets to be moved into the bucket above said axis, rotate the bucket to invert

the packets and discharge the packets from the inverted bucket into the carton.

8. Apparatus according to claim 6, comprising vibrator means mounted on the rotor for effecting vibration of the bucket and means for causing the vibrator to vibrate the bucket when the latter is at the position below said axis.

9. Apparatus according to claim 6, wherein the transfer assembly comprises relatively movable parts for applying pressure to the packets.

10. Apparatus according to claim 6, wherein the transfer assembly is constructed and arranged to apply a light pressure to the packets as it moves them along the packet support into the bucket.

15 11. Apparatus according to claim 6, wherein the loader assembly embodies a reciprocable part arranged to repeatedly squeeze the packets as they are discharged from the bucket into the carton.

12. Apparatus according to claim 6, wherein the 20 rotor has two buckets diametrically disposed so that when one bucket is vertically above the axis of the rotor the other is vertically below, and wherein the drive means are operable to cause the transfer assembly to push a column of packets into the bucket above said axis and simultaneously to cause the loader assembly to discharge a column of packets from the bucket below the axis into a carton.

13. Apparatus according to claim 12, wherein each 30 bucket has two chambers longitudinally thereof, each of which is adapted to receive a predetermined number of packets.

14. Apparatus according to claim 12, wherein a medially located divider extends longitudinally of each bucket dividing it into two chambers, each of which is adapted to receive a predetermined number of packets.

15. A loader comprising a rotor rotatable about a predetermined axis, diametrically disposed buckets mounted on the rotor, said buckets having open ends 40 for receiving in one position a column of packets and in another position discharging said columns of packets, means for selecting and introducing a group of a predetermined number of packets through one open end into the bucket in the one position, said means comprising a horizontal support arranged at a level corresponding to the level of the bucket in said one position, means for advancing packets resting on their edges in face-to-face relation along said support, means arranged at a predetermined position along said support to separate a predetermined number of packets from the succeeding packets, a pusher located at said predetermined position for movement from a retracted position to a position behind the separated packets, means for effecting reciprocation of the pusher parallel to the support in one direction to advance the separated packets along said support into the bucket and in the other to return for a succeeding group of packets, means for rotating the rotor to reverse the position of the buckets, means at said other position for supporting an empty open-ended carton adjacent an end of the bucket at said other position, and means for discharging the packets from the bucket into the carton.

16. A loader comprising a rotor rotatable about a predetermined axis, diametrically disposed buckets mounted on the rotor, said buckets having open ends 65 for receiving in one position a column of packets and in another position for discharging the packets, means

for selecting and introducing a group of a predetermined number of packets through one open end into a bucket at the one position, said means comprising a support at said one position, means associated with the support for advancing packets along the support toward the bucket, a selector arranged at a predetermined position to separate a group of a predetermined number of the advancing packets from the succeeding packets, a pusher supported for movement from a retracted position to a position between the separated packets and the succeeding packets and for movement along the support to push the separated packets into the bucket, power-operable means for effecting operation of the selector and pusher, switch means movable by the selector at said predetermined position to cause the power-operable means to move the pusher to said position between the separated packets and the succeeding packets, switch means operable by the pusher at said position to cause the power-operable means to move the pusher along the support, means for rotating the rotor to reverse the position of the buckets, means at said other position for supporting an empty open-ended carton adjacent an end of the bucket at said other position, and means for discharging the packets from the bucket into the carton.

17. A loader comprising a rotor rotatable about a predetermined axis, diametrically disposed buckets mounted on the rotor, said buckets having open ends for receiving in one position a column of packets and in another position discharging the packets, means for selecting and introducing a group of a predetermined number of packets through one open end into a bucket at said one position, said means comprising a horizontal support at the level of the bucket in said one position, means associated with the support for advancing packets along the support, a selector arranged alongside the support, said selector being operable at a predetermined position to separate a group of the advancing packets from the succeeding packets, a pusher supported above the horizontal support at said predetermined position movable to a position between the separated group of packets and the succeeding packets, a retainer support above said support forwardly of the pusher, a motor for effecting movement of the pusher into said position behind the selected packets to confine the packets between it and the retainer support and means for simultaneously advancing said pusher and retainer support along the horizontal support to advance the separated group of packets into the bucket, means for rotating the rotor to move the bucket at the one position to the other position to invert the packets therein, means at said other position for supporting a carton in alignment with the bucket at said other position, and means for discharging the inverted packets from said bucket into the carton.

18. Apparatus according to claim 17, comprising vibrator means associated with each bucket, means for effecting vibration of the vibrator means associated with the bucket at the discharge position, and means associated with the discharge means for repeatedly applying pressure perpendicularly to the faces of the packets as they are discharged.

19. In a loader, an elongate bucket open at its opposite ends, means supporting the bucket for movement about a horizontal axis from an upright position above said axis to an inverted position below said axis, means at the upright position of the bucket at one open end

thereof when the bucket is in said upright position for advancing a column of a predetermined number of packets supported on edge in a column in which the packets are arranged face-to-face through said open end into the bucket, means for inverting the filled bucket, means at the inverted position of the bucket at the opposite end of the bucket for supporting an open-ended carton in registration with said opposite end of the bucket, and means for discharging the packets from the inverted bucket into the open-ended carton.

20. Apparatus according to claim 19, wherein the means for advancing the packets into the bucket at its position above the axis comprises means for confining the selected group of packets at its leading and trailing ends under light pressure as the packets are advanced into the bucket, and wherein the means for discharging the packets from the inverted bucket into the carton comprises means for confining the packets at the leading and trailing ends under light pressure as they are discharged into the carton.

21. Apparatus according to claim 20, wherein said means confining the ends of the packets as they are moved into the bucket compresses the group of packets to a length corresponding to the length of the bucket.

22. Apparatus according to claim 20, wherein said means confining the packets as they are discharged into the carton compresses the group of packets to a length corresponding to the length of the carton.

23. Apparatus according to claim 20, wherein said means confining the packets as they are discharged into the carton repeatedly squeezes the packets.

24. Apparatus according to claim 20, wherein there is means for moving the confining means in each position of the bucket to a position at the ends of the bucket such that the bucket is capable of being moved from its upright position between said confining means at said position to its inverted position between said confining means at said inverted position, and there are means situated between said two positions for confining the packets within the bucket during movement of the bucket from its upright position to its inverted position.

25. Apparatus according to claim 19, wherein the means for advancing the packets into the bucket at its position above the axis comprises means for confining the selected group of packets at its leading end and trailing end and the confining means at the leading end is yieldably supported relative to the confining means at the trailing end so as to apply light pressure to the packets confined between it and the confining means at the trailing end.

26. Apparatus according to claim 20, wherein the confining means comprise spaced members between which the packets are confined and means supporting the spaced members for movement in unison to advance the packets through said one open end of the bucket into the bucket to a position in which the leading and trailing members are flush with the opposite open ends of the bucket.

27. Apparatus according to claim 26, wherein the leading one of the confining members which moves the packets into the upright bucket moves longitudinally through the bucket.

28. In a loader, an elongate bucket open at its opposite ends, spaced frame members, means supporting the bucket between said frame members with its opposite

ends substantially engaged with said frame members for rotation about a horizontal axis from an upright position to an inverted position, said frame members containing openings at the upright and inverted positions of the bucket through which the packets are adapted to be advanced into one of the open ends of the bucket at the upright position and discharged through the opposite open end of the bucket at the inverted position, said frame members closing the open ends of the bucket as it is moved from said upright position to said inverted position, means for advancing a predetermined number of packets through said opening in the frame at the one end of the upright bucket into the bucket, said means being operable to hold the packets within the bucket until it is rotated, means supporting an empty carton at said inverted position, and means for discharging packets through the opening in the frame at the opposite end of the inverted bucket from the bucket into the carton, said means being operable to hold the packets compressed to a length no greater than the length of the carton as they are discharged into the carton.

29. In a loader, a bucket open at its ends, means supporting the bucket for movement about a horizontal axis from an upright position to an inverted position, means for selecting and introducing a predetermined number of packets through one open end into the bucket in said upright position, means for effecting movement of the bucket from said upright position to said inverted position, means at the inverted position of the bucket for supporting an open-ended carton in registration with the opposite open end of the bucket in its inverted position, means for discharging the packets from the bucket through said opposite end into the carton, and means at the ends of the bucket between which the open ends of the bucket are confined as it is moved from said upright position to its inverted position.

30. Apparatus according to claim 25, wherein the confining means comprise longitudinally spaced back-up and pusher members between which the packets are confined, and means for advancing the back-up and pusher members in unison to move the back-up member through the one open end of the bucket longitudinally thereof to a position flush with the opposite end and to move the pusher member to a position flush with the one open end.

31. In a loader, diametrically disposed buckets mounted back-to-back for rotation about a horizontal axis, said buckets being open at their ends, means supporting the buckets for rotation about said horizontal axis to move first one bucket and then the other from an upright position to an inverted position, means for selecting and introducing a predetermined number of packets through one open end of the one of the buckets in the upright position, means for supporting an open-ended carton in a position such that one open end is in registration with the opposite open end of the bucket at its inverted position, and means for discharging the packets from the bucket at its inverted position into the carton, said means for selecting and introducing a predetermined number of packets into the bucket in the upright position comprising conveyor means for advancing packets on edge in face-to-face relation toward the open end of the bucket, means for separating a predetermined number of packets from the advancing packets, and longitudinally spaced transfer means be-

tween which the separated packets are delivered, said latter means being movable in unison and tandemly to positions in which the leading member passes through the bucket to a position flush with the opposite end and the trailing member to a position flush with the one end.

32. Apparatus according to claim 31, wherein there are spaced separating members mounted on the conveyor for intercepting the advancing packets at intervals such as to select a predetermined number of packets from the advancing packets, and means for causing the trailing one of the separated members at a predetermined position to push the packets ahead of it forwardly a predetermined distance to provide a gap between the trailing end of the selected packets and the leading packet of the succeeding packets.

33. Apparatus according to claim 31, wherein the transfer means between which the selected packets are confined comprises a back-up member supported in a position in the path of the advancing packets and a pusher member supported above said path, and means for moving the pusher member from above said path downwardly into said gap between the trailing end of the selected packets and the leading packet of the succeeding packets.

34. Apparatus according to claim 32, wherein the separating members are pivotally mounted on the conveyor and there is means operable as the separating members are moved forwardly to tilt the trailing one of the separating members forwardly to separate the packets forwardly thereof from the succeeding packets.

35. Apparatus according to claim 33, comprising a reciprocably supported carriage, means mounting the back-up member on the carriage in the path of the advancing packets, means mounting the pusher member on the carriage above said path for reciprocable movement into and out of said path of movement of the packets, means on the carriage for effecting reciprocable movement of the pusher member to at times move the pusher member into the gap between the selected packets and the succeeding packets to confine the selected packets, and means for effecting movement of the reciprocably movable carriage at said times and hence the back-up member and pusher member in unison toward the bucket.

36. In a loader, an elongate bucket supported for rotation about a horizontal axis from an upright to an inverted position, said bucket being open at its ends, a divider support extending longitudinally of the bucket dividing the bucket into two side-by-side chambers for receiving two columns of packets, means for selecting and introducing predetermined numbers of packets into one of the open ends of the buckets into said chambers therein at said upright position of the bucket, means for supporting an open-ended carton in a position for registration with the opposite end of the bucket in its inverted position for receiving the packets, means for discharging packets from the bucket in its inverted position into the carton, and means for introducing a divider strip into the divider support between the chambers of the upright bucket prior to advancing the packets into said chamber, said means for discharging the packets from the bucket in its inverted position being operable to move the divider strip from the divider support together with the packets from the bucket into the carton.

37. In a loader, a bucket supported for rotation about a horizontal axis from an upright to an inverted position, said bucket being open at its ends, a support for receiving a divider strip longitudinally of the bucket to divide it into two longitudinally extending side-by-side chambers, means for selecting and inserting predetermined numbers of packets through one open end of the bucket into said chambers at said upright position of the bucket, means for supporting an openended carton in a position of registration with the opposite end of the bucket in its inverted position for receiving the packets, means for discharging the packets from the bucket in its inverted position into the carton, a reciprocable carriage mounting the means for selecting and inserting the packets into the bucket, means for reciprocating the carriage to advance the means for selecting and inserting the packets into the bucket and for retraction preparatory to the next operation, and means supported by the carriage operable by retraction of the carriage to move a divider strip through the opposite end of the bucket in the upright position into said divider support preparatory to advancing the packets into the bucket.

38. Apparatus according to claim 37, wherein said strip support comprises pairs of opposed spring fingers between which an edge of the divider strip is drawn by said last means.

39. Apparatus according to claim 37, wherein said divider strip support comprises a channel at the bottom of the bucket and pairs of opposed spring fingers mounted therein between which an edge of the divider strip is drawn by said last means.

40. Apparatus according to claim 37, comprising a magazine supporting a stack of divider strips with the end strip at one end exposed and wherein the last means is supported by the carriage adjacent to the end strip in the magazine when the carriage is in the extended position and is movable therewith during retractive movement of the carriage to remove the end strip from the magazine and transfer it to the strip support in the bucket.

41. Apparatus according to claim 40, wherein said last means is provided with suction picking elements for picking the end strip from the end of the magazine.

42. Apparatus according to claim 37, wherein the bucket contains a longitudinally extending opening at the top medially of its width and the last means is movable by the carriage reciprocably from a position opposite the magazine at one end of the bucket through said top opening to the opposite end and there is means for effecting vacuum picking of the end strips from the magazine at the one end and for releasing the strip from the picker at the other end.

43. Apparatus according to claim 42, comprising means mounted on the bucket across the top opening for preventing the divider strip from falling through said opening when the bucket is inverted, said means being yieldably supported to permit the last means to move longitudinally of said top opening in reciprocation.

44. In a loader, a bucket rotatable from an upright position to an inverted position about a horizontal axis, means for selecting and advancing predetermined numbers of packets along a support under slight compression into one of the open ends of the bucket in its upright position, means for inverting the bucket, means

for vibrating the inverted bucket, means for supporting an empty open-ended carton in a position to be in registration with the opposite end of the bucket when in its inverted position, and means for discharging the packets from the bucket while under slight compression into the carton.

45. Apparatus according to claim 44, wherein said discharge means comprises a back-up member and a pusher member movable in unison longitudinally of the bucket and means for effecting repeated short reverse strokes to the pusher member while it is being moved longitudinally through the bucket.

46. In a loader, diametrically disposed buckets mounted back-to-back, means supporting the buckets for rotation about a horizontal axis from an upright position above said axis to an inverted position below said axis, means for depositing a predetermined number of packets under slight compression in the bucket at the upright position, means for rotating the buckets to reverse the position of the buckets, means supporting an open-ended empty carton in a position of registration with an end of the bucket in the inverted position, means for discharging the packets from the inverted bucket under light compression into the carton, vibrating means associated with each bucket, and means operable by movement of the bucket to its inverted position to initiate operation of the vibrating means associated therewith.

47. Apparatus according to claim 46, wherein the means supporting the buckets comprises a shaft and means yieldably mounting the buckets on the shaft.

48. Apparatus according to claim 47, wherein the means supporting the buckets comprises a shaft supported for rotation about a horizontal axis, a rotor mounted on the shaft, and means yieldably mounting the buckets on the shaft back-to-back.

49. In a loader, diametrically disposed buckets mounted back-to-back, means supporting the buckets for rotation about a horizontal axis from an upright position about the axis to an inverted position below said axis, each bucket being divided into two side-by-side open-ended chambers extending longitudinally of the axis of rotation, means for depositing a predetermined number of packets in the chamber of the bucket above the axis under light compression, means for rotating the buckets to reverse their positions, means for supporting an empty carton with one end open in a position of registration with an end of the bucket in the inverted position, means for discharging the packets from the inverted bucket under light compression into the carton, pairs of vibrators associated with the respective buckets, means operable by movement of a bucket to its inverted position to initiate operation of the vibrators associated therewith, and means for continuing said vibration until the packets are discharged into the carton.

50. In a loader, diametrically disposed buckets mounted back-to-back for rotation about a horizontal axis from a receiving upright position at the upper side of said shaft to a discharge inverted position at the lower side of said shaft, means for selecting a predetermined number of packets and depositing them in the bucket at the upper side of the shaft, means for supporting an open-ended carton in a position of registration with an open end of a bucket at the lower side of the shaft, means for discharging the packets from the bucket at said lower side of the shaft into the carton,

and means for moving successive empty cartons to said position of registration with the inverted bucket and moving the filled cartons away from said position.

51. In a loader, diametrically disposed buckets mounted back-to-back for rotation about a horizontal axis to move first one and then the other from an upright position above said axis of the rotor to an inverted position below said axis, means for selecting and depositing a predetermined number of packets in the bucket above said axis, means for rotating the rotor about said axis to reverse the positions of the buckets, means for supporting an open-ended carton in a position of registration with the bucket at the inverted position, and means for discharging the packets from the inverted bucket into the carton, said means for selecting and depositing the packets in the bucket above said axis comprising a support situated in a horizontal plane at the level of the bottom of the bucket above said axis, means for owing the packets along said support toward the bucket with the packets resting on their edges in face-to-face relation and in a column, and means for ejecting jets of air toward the advancing packets to hold them upright as they are advanced.

52. A method of loading a carton of a predetermined

length with a predetermined number of tea bags, comprising advancing a predetermined number of tea bags in single file and resting on one edge face-to-face under light compression perpendicular to their faces to a position for inversion of the group, inverting the group by rotating them to a position such that they rest on their opposite edges, vibrating the bags at said inverted position and advancing the bags while continuing to effect their vibration under light pressure perpendicular to their faces into said carton.

53. A method according to claim 52, comprising subjecting the bags in their inverted position to repeated squeezing and relaxing action perpendicular to their faces to condense the column to a predetermined length and advancing the condensed column into the carton.

54. A method according to claim 52, comprising advancing two columns of tea bags side-by-side to said place of inversion, supporting a divider strip at said place of inversion for maintaining the tea bags in the columns separate from each other and discharging the separated strip together with the tea bags into the carton.
